U.S. Cl. D12—125

FIG. 1 is a top perspective view of one end of a reflective bicycle pedal showing our new design;

FIG. 2 is a top perspective view of the opposite end thereof;

FIG. 3 is an elevational view of the left end of FIG. 1;

FIG. 4 is an elevational view of the left end of FIG. 2;

FIG. 5 is a sectional view taken along line 5—5 of FIG. 1;

FIG. 6 is a top perspective view of a reflective bicycle pedal showing a second embodiment of our new design, the sole difference being that the reflective surfaces are flush with the sides of the pedal as best illustrated in FIG. 7; and

FIG. 7 is a sectional view taken along line 7—7 of FIG. 6.

The characteristic feature of our design resides in the elongate reflective surfaces on the sides of the pedal.

We claim:

The ornamental design for a reflective bicycle pedal, as shown and described.
